UNITED STATES PATENT OFFICE.

GEORGE C. KEENE, OF CINCINNATI, OHIO, ASSIGNOR OF TWO-THIRDS TO
LONGLEY L. SAGENDORPH AND HARLAN P. LLOYD, BOTH OF SAME
PLACE.

AUTOMATIC FEEDING MECHANISM.

SPECIFICATION forming part of Letters Patent No. 367,527, dated August 2, 1887.

Application filed May 25, 1887. Serial No. 239,294. (No model.)

To all whom it may concern:

Be it known that I, GEORGE C. KEENE, a citizen of the United States, residing at Cincinnati, in the county of Hamilton, State of Ohio, have invented certain new and useful Improvements in Automatic Feeding Mechanisms, of which the following is a specification.

The several features of my invention and the advantages arising from their use, conjointly or otherwise, will be apparent from the following description.

In the accompanying drawings, forming part of this specification, Figure 1 is a perspective view of a machine for corrugating sheet metal provided with my improved feeding mechanism. Fig. 2 is an elevation of the right hand end of the machine, as shown in Fig. 1, the end frame being removed. Fig. 3 is an elevation of the left-hand end of the machine. Fig. 4 is a view illustrating the means for securing the striking-pin in the roller.

The device is particularly useful in corrugating-machines of the type shown, but may also be applied to other machines requiring a similar feed. The rolls A are suitably mounted in journal-boxes in the side frames, B. The rolls shown are provided with two sets of corrugating-ridges, one set, a, being fine, the other set, a', being coarse. There are usually blanks a² between the two sets of corrugating-ridges.

The stationary table D is supported in front of the rolls in any suitable manner, as by the bracket C. The sliding table E rests on the table D, and is provided with tongues e, which fit in grooves d in the table D and guide the table E in its movements on the table D. The bent lever F is fulcrumed to the lug G, projecting downward from the table D. The lever F has a short arm, f, which extends upwardly and fits in the opening e' in the table E. The other arm, f', extends toward the rolls and is bent downward at the end.

The coiled springs G'—one at each end of the machine—extend from the table D to the table E, in such a position as tends to draw

the table E away from the rolls. The sliding table E is preferably provided with the gage E'.

The pin P projects from the end of the lower roll, A. The slot a³ extends diametrically across the end of the roll A, except at the center, where the shaft end is cast. The pin P consists of a bolt, p, whose head engages under the edges of the slot a³. The pin p passes through the sleeve p', the latter bearing against the face of the end of the roll. A nut, p², clamps the whole firmly in position. This arrangement permits the pin P to be adjusted with relation to the center of the roll.

The mode of operation of the device is as follows: The sheet to be corrugated is placed on table E, against the gage E', its other edge projecting beyond the table toward the rolls. The machine is now set in motion, the gearing being so arranged as to turn the rolls in the direction indicated by the arrows in Fig. 2. When the pin P strikes the arm f of the lever F, the latter is depressed and causes the arm f to throw the sliding table E toward the rolls. This movement of the table E carries the sheet of metal inward until it is grasped by the rolls and crimped between them. The mechanism is so adjusted that the sheet is placed between the rolls just at the beginning of the corrugations. By changing the pin P to the other side of the center of the rolls the sheet of metal is moved forward in time to be crimped by the other set of corrugations.

What I claim as new, and desire to secure by Letters Patent, is—

1. The combination of the stationary table D, sliding table E, bent lever F, having short arm f, connected to table E, long arm f', and means for operating the bent lever F, substantially as and for the purposes specified.

2. The combination of the stationary table D, sliding table E, bent lever F, having short arm f, connected to table E, and long arm f', and roll A, provided with pin P, substantially as and for the purposes specified.

3. In a corrugating-machine, the combination of rolls A A, provided with corrugations

a' and blanks a^2 , table D, sliding table E, bent lever F, and roll A, provided with adjustable pin P, substantially as and for the purposes specified.

5 4. The combination of the stationary table D, sliding table E, bent lever F, having short arm f, connected to sliding table E, and long

arm f', roll A, provided with transverse slot a^3 , and pin P, adjustable in said slot, all substantially as and for the purposes specified.

GEORGE C. KEENE.
